TOW TRACTOR

Warner K. Brown, Battle Creek, Mich., assignor to Clark
Equipment Company, a corporation of Michigan

Filed Oct. 25, 1961, Ser. No. 67,261

Term of patent 14 years

(Cl. D14—3)

FIG. 1

Des. 192,794

PAGE 2

FIG. 2

FIG. 3

The dominant features of my design reside in the portions illustrated in solid lines.

I claim:

The ornamental design for a tow tractor, as shown and described.
